AIR PISTOL

William S. Wells, Palo Alto, Calif., assignor to
Daisy Manufacturing Co., a corporation of
Michigan

Application March 13, 1939, Serial No. 261,621

17 Claims. (Cl. 124—11)

My invention relates to guns, more particularly to guns powered by air under compression.

It is an object of my invention to provide an improved air powered gun.

(1) Of the single shot type capable of being charged by a single stroke of a pump, without sacrificing velocity and accuracy of operation.

(2) Of the single shot type having instantaneous firing action without resorting to the use of a hammer.

(3) Of the single shot type capable of holding an air charge over a prolonged period of time.

(4) Of the single shot type capable of velocity control adjustment.

(5) Of the repeater type capable of firing a substantial number of shots at a velocity above a practical minimum value on one charge of air.

(6) Of the repeater type which efficiently utilizes available space therein for air storage purposes.

(7) Of the repeater type having exceedingly quick cut-off of air supply following each firing of the gun.

(8) Of the repeater type having air conserving features for utilizing to its maximum extent the air stored up in the gun.

(9) Capable of loading by gravity feed.

(10) Capable of loading when held at an angle below the horizontal as well as when held at an angle above the horizontal.

(11) Capable of holding a shot in firing position without the use of mechanical restricting means.

(12) Constructed to provide sleeve action operation for loading and/or cocking of the same.

(13) Constructed to provide bolt action operation for loading and/or cocking of the same.

(14) Embodying one or more of the above features and so constructed as to lend itself to economical manufacture.

(15) Of simplified construction enabling the gun to be readily assembled or disassembled for repair or replacement of parts if needed.

Additional objects of my invention will be brought out in the following description of the same, taken in conjunction with the accompanying drawings wherein:

Fig. 1 is a view in section of a gun of my invention in the form of a pistol of the single shot type.

Fig. 2 is a side elevational view of the same with the pump piston slightly extended.

Fig. 3 is a view in section taken along the line 3—3 of Fig. 1.

Fig. 4 is a view in section taken along the line 4—4 of Fig. 1.

Fig. 5 embodies a plurality of views illustrating the manner of operation of a discharge valve forming an important feature of the gun assembly illustrated in Fig. 1.

Fig. 6 is a view in section of another embodiment of my invention as applied to a pistol of the repeater type.

Fig. 7 is an elevational view of the pistol of Fig. 6, with the pump barrel in partially extending position.

Fig. 8 is a view in section taken along the line 8—8 of Fig. 6.

In general my invention involves the application of a plurality of improvement features to pistols and rifles powered by air, to impart to such guns operating and firing characteristics heretofore unknown in guns of this general character on the market. Certain of these features are peculiarly applicable to guns of the single shot type, others of these features are especially adaptable to guns of the repeater type, whereas certain of the features are equally adaptable for guns of either type. These various features will be described in detail in connection with the description of the embodiments as illustrated in the drawings.

The single shot pistol illustrated in Fig. 1 is adapted to be charged with air by the stroke of a single stroke pump. The pump comprises a tube 1 closed at the breech end of the gun by a breech block 3 forming an element of a discharge valve assembly. This block is formed with a valve opening 5 facing the interior of the pump, which valve opening is connected by a channel 7 at right angles thereto, with the gun barrel 9 just behind the firing position 11 of a pellet or other type of shot customarily employed in pistols or rifles which are powered by air. The valve opening 5 is surrounded and partially covered by a valve seat 13 of special design, the purpose of which will be subsequently explained in the operation of the gun. This valve seat 13 is of a resilient stretchable material such as rubber and frustro-conical in shape, with a base substantially equal to the interior of the pump cylinder 1, and covering the surface of the breech block surrounding the valve opening therein. The valve 15 seats upon the smaller exposed end of the valve seat 13 and has a valve stem 17 extending through the valve seat 13, the valve opening 5 and through a longitudinal channel formed through the breech block 3 to receive the same. The valve stem terminates a

50

10

short distance beyond the rear of the breech block to which end of the stem is attached a nut 19. A conical spring 21 under compression between the rear surface of the breech block and the nut 19 serves to normally hold the valve 15 against the valve seat 13.

The pump includes a plunger which comprises a base member 23 of cylindrical shape and of a diameter to slidably fit within the pump barrel 1, this base member being provided with an integral extension or pin 25 in the direction of the valve 15. A non-porous cup-shaped leather washer 27 is adapted to fit over the pin with its bottom contacting the base member 23. A washer 29 of resilient stretchable material such as rubber is fitted within the leather cup-shaped member 27, and against this rubber washer there is placed a compression washer 31 of a hard material such as metal, and the whole assembly including the leather cup-shaped member 27, the rubber washer 29 and the metal washer 31 is compressed and maintained under compression by the application of a nut 33 to the extension or pin 25 which has been threaded to receive the same. The plunger is pivotally secured to a plunger rod 35 which extends through a guide and supporting bearing 37 at the muzzle end of the gun and terminates in a finger grip nut 39, enabling the plunger rod to be conveniently grasped and withdrawn in preparation for a compression stroke.

The plunger rod 35 has formed integral therewith along its upper edge, a rib 41 spaced a short distance from the grip nut 39 and extending substantially the full length of the plunger rod, the guide bearing 37 being slotted to provide a passage 43 for this rib, as the pump plunger rod is withdrawn. The guide bearing 37 has a sector slot 44 formed in the rear edge thereof, enabling the pump plunger to be rotated through an angle thus swinging the rib out of alignment with the rib slot 43 in the bearing, and locking the plunger in position against the expansive force of the air under compression in the pump at the completion of a compression stroke.

In the pump under consideration, the space between the plunger 22 and the valve 15 constitutes an air compression chamber 46, which at the completion of a compression stroke is necessarily small, but the air trapped therein however, is under exceedingly high compression, thus assuring proper initial conditions for imparting high velocity to a discharged pellet.

In the event that a lower value of compression may be desired, as when a pistol of this type is to be placed in the hands of a child as a play toy, the reduction in compression can be very readily realized by effectively shortening the length of the plunger stroke. Such reduction in stroke is obtained by providing the plunger rod 35 at spaced intervals with transverse openings 45, in a selected one of which is placed a stop in the form of a cotter pin 47 or equivalent means, which upon withdrawal of the plunger rod will strike against the guide bearing 37 thus permitting only a percentage of a full stroke of the plunger, depending upon the opening selected to receive the cotter pin 47.

Operation of the valve 15 is controlled from a trigger 48 operating through a tappet 51 by means of an interconnecting rod 53, one end of which bears against the shank of the trigger, whereas the other end bears against one end of the tappet, holding the other end of the tappet in light contact against the end of the valve 15

stem 17. The trigger 48 and the tappet 51 are both pivotally mounted in a narrow trough or channel 55 which is soldered or otherwise affixed to the under surface of the pump barrel 1 at the breech end of the gun. This trough extends a slight distance beyond the breech end of the pump to provide room for the location of the tappet 51 in cooperating relationship with the valve stem 17 as described.

The gun barrel 9 is supported along the upper surface of the pump barrel 1, extending slightly beyond the breech end of the pump. Just behind the opening of channel 7 into the gun barrel, the barrel is provided with a second opening 52, in its upper surface for loading purposes. A pellet dropped into the barrel at the proper time through this opening, is urged to its firing position 11 just ahead of the opening from the channel 7 into the gun barrel.

Placing the pellet in its discharge position 11 is accomplished through the operation of a breech pin 53 which is slidably fitted into the breech end of the gun barrel, the inserted end of the pin being tapered while the exposed end is provided with a flange 54. The pin has a flattened or grooved intermediate portion 55 adapted to receive a set screw 57 threaded through the upper surface of the gun barrel at a point just behind the loading opening 52, such set screw serving to limit the movement of the breech pin 53 in the gun barrel between the firing position 11, and the loading position wherein the opening 52 to the gun barrel is uncovered. A breech pin spring 59 positioned under compression about the exposed portion of the breech pin, between the breech end of the barrel and the flange 54 exerts a continual force tending to urge the breech pin to its loading position.

The breech pin is magnetized and is adapted, when cooperating with a pellet to place it in firing position, to hold the pellet in its firing position until discharged. This avoids the necessity for employing frictional or other mechanical means for doing the same thing.

The entire assembly thus far described is slidably receivable in a sleeve 61, and when inserted in such sleeve to its extreme position, determined by contact of the rear end of the trough 55 against the rear end 62 of the sleeve, the breech pin 53 will be urged to its firing position against the opposing force of the spring 59. This position of the breech pin is illustrated in Fig. 1.

The sleeve 61 in being formed, is arched at its upper edge to cooperate with the pump barrel in forming a magazine 63 for holding a plurality of pellets. The front end of the magazine is provided with an opening 65 for the loading of pellets therein, and at its breech end is provided with an inspection slot 67 for enabling one to determine the contents of the magazine. The set screw 57, previously referred to as determining the maximum extent of travel of the breech pin, is so constructed as to include a right angle portion 69 extending along the upper edge of the gun barrel in the direction of and terminating at the loading opening 52 to the gun barrel, and acts as a stop to guide the pellets from the magazine through the loading opening.

With the pump and gun barrel assembly urged to maximum extreme position in the sleeve as indicated in Fig. 1, the opening 65 to the magazine will normally be closed by a short rib 71 integrally attached to the upper edge of the gun barrel and extending into the front end of the magazine.

The sleeve 61 at its lower edges straddles a handle or stock 73 to which it is rigidly secured by means of bolts or the like. A trigger guard 15 may be attached at one end to the stock 73 of the gun, and at its other end is looped around a securing bolt 17 extending through both walls of the sleeve, such loop terminating in a short projection 78 extending in the direction of the front end of the trough 55.

The above described arrangement enables sleeve 10 action in the loading of the gun, the operation of which may be briefly explained as follows. By grasping the stock 73 of the pistol in one hand and the pump and gun barrel assembly in the other, the gun barrel and pump assembly may be 15 partially withdrawn from the sleeve, the extent of withdrawal being determined by the trigger guard extension 78 against which the front end of the trough 55 will abut. In such withdrawn position the rib on the upper surface of the gun barrel will no longer block the opening 55 to the magazine, thus enabling the magazine to be loaded or filled with shot. At the same time the breech pin 52, due to the resulting expansion of 20 the breech pin spring 58 permitted by the partial withdrawal of the pump and gun barrel assembly, will be withdrawn to its loading position thereby exposing the loading opening 52 to the barrel, whereupon one of the pellets will drop into the gun barrel and will be held to the breech pin by 25 magnetic attraction. Upon restoring the pump and gun barrel assembly again to the position indicated in Fig. 1, the opening to the magazine will again be blocked, thus precluding loss of shot, and the pellet which had previously been permitted to drop into the barrel, will be urged by the breech pin to its firing position 11 as indicated in Fig. 1. The gun is now in condition to be fired providing 30 the air in the pump chamber is under compression. To obtain a highly compressed charge of air in the pump, the valve 15 is unseated by pressure against the trigger and serves as the inlet valve to the pump. When thusly unseated, it 35 enables withdrawal of the plunger rod accompanied by a charge of air into the pump. The valve 15 is then allowed to close by release of the trigger, and the charge of air is compressed by 40 restoring the pump plunger to its original position, and locking it as previously described. A subsequent pull on the trigger will again unseat the valve 15, this time enabling the discharge of 45 the compressed air behind the pellet which had been previously described as having been placed in firing position. The valve 15 thus performs the dual purpose of the pump intake valve and 50 the gun discharge valve.

If, in the act of withdrawing the plunger rod from the pump, the gun be pointed at an angle above the horizontal, loading of the gun may be effected simultaneously with the pumping operation.

In the operation of the above described pistol, the plunger construction and the valve construction are of the utmost importance.

Successful and satisfactory operation depends first upon developing and retaining a high value of compression in the pump chamber. The pivotal connection of the plunger head to the plunger rod will assist materially in obtaining this high compression by reason of the fact that slight axial displacement or wobbling of the plunger rod in the operation of the pump, will not throw the plunger head out of alignment in the pump barrel, thus enabling the plunger head to retain a tight undistorted fit in the barrel.

Of more importance however, in connection with the functioning of the plunger head, is its construction, which not only materially contributes toward obtaining the necessary high compression, but also serves to retain such high compression and inhibit leakage from the pump chamber thereafter. The plunger head construction enables this to be accomplished by reason of the fact that the rubber washer 28, when placed under longitudinal compression by the nut 33, will expand laterally and exert a positive lateral pressure of great force against the walls of the leather cup at all times, even in the absence of air pressure in the pump chamber.

In accordance with prior art pump construction, plungers employed leather cup-shaped elements, but relied upon the increasing pressure in the pump chamber during compression strokes for effecting a tight fit between the leather cup and the wall of the pump barrel. Any crease or wrinkle in the leather cup element, or the presence of a foreign body between the cup and the interior wall of the pump, will necessarily bring about aggravated conditions of leakage upon the development of pressure in the pump. In the construction described by me, the lateral pressure against the leather cup is a positive pressure existing at all times and such pressure may be made to exceed any pressure which might be developed in the pump itself. Being directed laterally against the inner surface only of the cup-shaped washer, such pressures will effect a tight leak-proof fit of the plunger in the pump barrel. I have found, in guns embodying the plunger construction described by me, that a charge of air at times will be retained therein with but very little loss, for periods of the order of months at a stretch.

Another characteristic considered quite necessary in the obtaining of successful operation of a pistol of the type described, resides in obtaining snappy discharge of the air under compression at the instant of firing. The air must be released suddenly and with practically no loss of pressure. The special valve assembly described by me functions to realize such operation. In the first place, the discharge channel to the gun barrel is of minimum length and of substantially uniform cross-sectional area throughout, allowance being made for the valve stem which passes through a portion of such channel.

The operation of the valve itself which is of utmost importance, is best described by referring to the views in Fig. 5. Fig. 5A illustrates the valve and valve seat in normal position with no compression in the pump. Upon the completion of a compression stroke, the pressure developed in the air chamber will urge the valve to the rear slightly, at the same time distorting the valve seat under compression, to give it a form somewhat as indicated in Fig. 5B. In pulling the trigger to effect the firing of the pistol the valve will be gradually urged forward, but due to the highly compressed air acting against the rubber valve seat, the valve seat will stretch under tension and follow the movement of the valve until the degree of stretch has reached a value, where the valve seat will no longer keep up with the valve, and separation will occur. Such separation will be exceedingly fast, for at the instant that such separation occurs, the stretchable valve seat is under considerable tension, and will instantaneously snap back to its normal shape. Therefore, the air under compression in the chamber will be discharged instantaneously and

the full force thereof will be directed against the pellet in the gun barrel with very little, if any, drop in pressure.

Were the valve seat described by me omitted from my valve assembly, the opening of the valve must necessarily involve a gradual enlargement of the space between the valve and its seat, resulting in a comparatively gradual release of air from the pump chamber. The full effect of the air under compression cannot be obtained or realized under such conditions.

The embodiment of my invention, as disclosed in Fig. 6, constitutes a pistol of the repeater type and in view of the fact that the air chamber must necessarily supply air sufficient for the firing of a number of pellets, the pump is of the multiple stroke type, thus enabling the building up of a desired pressure in a storage chamber of considerably greater volume than that provided for in the single shot type, where the entire volume of compressed air is discharged at each shot.

The pump in the pistol disclosed in Fig. 6 is provided with a stationary hollow tubular piston 81, anchored at its rear end in the breech block 82 and has the greater portion 83 of its wall section thinned down with respect to the rear end portion of the piston to form a shoulder 84. The front end of this piston is threaded to receive and hold an intake check valve and plunger assembly.

This assembly comprises a valve seat 87 threaded into the threaded end of the piston, which valve seat has integrally formed therewith, a tubular extension 99 in the direction of the muzzle end of the pistol. Such extension has its end threaded. A valve 101 which may take the form of a rivet, seats upon the valve seat 87 with its bifurcated shank inserted into the tubular extension 99, and is provided with a rubber sealing gasket 103. A rubber washer 105 fits over the tubular extension of the valve seat within the threaded portion of the piston and adjacent the valve seat, and is compressed against the undersurface of the valve seat by an internal compression nut 107 threaded into the threaded end of the piston.

Against this nut 107 and surrounding the tubular extension 99 of the valve seat, is a leather cup 109 which holds a rubber washer 111 against which is fitted a hard metallic washer 113 capable of being forced against the rubber washer 111 under compression by a clamping nut 115 threaded to the end of the tubular extension 99, thus giving a plunger construction along the lines of that described in Fig. 1. Over the thinner wall portion of the piston is reciprocally mounted a pump barrel 117, which is of a length to abut against the shoulder 84 of the piston, when the pump barrel is urged to its maximum position on the piston. This slideable pump barrel has fitted thereto at its front end, an intake check valve assembly 119.

This assembly involves a perforated cage 121 inserted in the front end of the pump barrel and internally threaded to receive a closure nut 123 which is formed with an air intake channel 125. This closure nut also functions as a valve seat in much the same manner as the tubular valve seat 87 of the piston. A valve 127 similar to that described in connection with the tubular valve seat of the piston is employed in the inlet check valve, the perforated cage 121 being so spaced from the valve head as to preclude the loss of the valve from the valve seat during use.

At the breech end of the pump, where the pump piston 81 is anchored to the breech block, the block is provided with a discharge channel 129 interconnecting the interior of the pump piston with the gun barrel 131, at a point just behind the firing position 130 of a pellet in the gun barrel.

The discharge valve constitutes an elongated resilient rubber plug 133 threaded to a valve stem 135, which stem extends through a portion of the discharge channel and through an opening in the breech block to a point beyond the rear end of the breech block in much the same manner as in the construction of Fig. 1. The valve is normally maintained in seated position by valve seating means within the pump piston. Such means includes a spring 137 bearing at one end against the rubber valve plug 133, and maintained under compression by a spring compression means involving a perforated cage 139 enclosing the piston check valve 101 and connected by a rod 141 to a loose fitting plunger disc 143 against which the other end of the spring 137 bears. A perforated partition 144 in the piston intermediate the perforated cage 139 and the plunger disc 143 may be employed to support the valve seating means and act as a guide bearing therefor.

The pump thus far described, by reason of its hollow stationary piston construction provides for a substantial air storage space therein, which will include all the available space between the piston check valve 101 and the breech block 82.

The gun barrel 131 in the embodiment disclosed in Fig. 6 does not rest upon the pump as in the single shot pistol of Fig. 1, but extends axially through an additional storage chamber formed by a tube 146 anchored at its rear end in the breech block 82 and closed at its front end by a plug 145 which is perforated to receive and support the discharge end of the gun barrel 131. At its rear end, the gun barrel extends through the breech block 82 and is supported at intermediate points by partitions 148 which are perforated to effect air connection between the chamber sections formed by the partitions. The storage chamber provided by the tube 146 is interconnected with the pump storage chamber by aligned openings in the storage chamber tube and the pump piston, and the pump cylinder when in its closed position. Such interconnection occurs at a point 151 between the perforated cage 139 and the plunger disc 143.

At its front end adjacent the pump cylinder, the auxiliary chamber tube 146 is provided with a pair of symmetrically disposed lugs 153 (only one being visible) and the pump piston at its rear end is likewise provided with similar lugs 155 in line with the first mentioned lugs, so that upon withdrawing the pump cylinder in the act of pumping, the lugs 155 on the cylinder will abut against the lugs of the auxiliary chamber, thus determining the length of the stroke of the pump.

Adjacent the front valve end of the pump cylinder, a locking collar 157 is attached, which is slotted and secured in position by a set screw 159 through the slot, thus permitting a limited rotational movement of the collar about the pump cylinder. The collar only partially extends about the cylinder and is formed with an extension 161 whereby upon the completion of a pumping operation and with the pump cylinder in the position indicated in Fig. 6, the locking collar may be rotated to effect interlocking engagement be-

tween the extension 181 and one of the lugs 183 on the auxiliary chamber tube. The pump cylinder is thereby locked against withdrawal.

Operation of the discharge valve in the embodiment described in Fig. 6 is effected through a hammer blow directed against the extended end of the valve stem 185, the blow being sufficient to effect momentary separation of the valve from the valve seat against the air compression and spring compression existing in the pump at the time. The hammer 163 is slidably positioned between the lower surface of the pump and the floor of the casing 165 which encloses the entire breech assembly of the gun, such hammer having a reduced longitudinal front section 167 adjacent the pump, leaving a space between this reduced longitudinal section and the floor of the casing 165. The lower edge of this longitudinal front section of the hammer is provided with a pair of notches 169 and 171 to receive the engaging end 173 of the trigger 175 which is pivotally supported between the side walls of the casing, with the finger grip portion extending through the floor of the casing within convenient reach of an operator. The notches 169 and 171 are adapted to be successively engaged by the trigger upon movement of the hammer from its normal position as shown in Fig. 8 in the direction of the muzzle end of the gun. The first notch 169 is somewhat deeper than the second, and functions as a safety notch, whereas the second notch 171 is of a somewhat shallower construction adapted to engage the trigger, whereby the hammer will be disengageably retained in such forward position.

A spring block 177 of wedge shape is provided just to the rear of the trigger 175 and between this spring block and the wide rear portion of the hammer is positioned the hammer spring 179. Upon the aforementioned forward movement of the hammer to engage the trigger, the spring block is urged against the trigger with the wedge shaped end contacting it at a point below the trigger pivot, causing the engaging end 173 of the trigger to pivot upwardly and successively enter the notches 169 and 171 in the hammer as they come into position thus cocking the gun. Simultaneously, the hammer spring 178 is compressed and is ready upon releasing the trigger to cause the hammer to fly back to its original position with sufficient force to unseat the valve as previously indicated.

Such rearward motion of the hammer is transferred to the valve stem 185 by means of a tappet 181 having one end 183 adapted to strike the extended end of the valve stem, while the other end 185 is adapted to be struck by the hammer 163. The end of the tappet 185 which is struck by the hammer is bifurcated to receive and permit slidable movement therethrough of an extension 187 to the rear of the hammer, which extension in the discharge position of the hammer as illustrated in Fig. 6, holds up one end 189 of a loading finger 191, which is pivotally supported by the side walls of the casing 165, with the other end 193 of the loading finger bearing against a magnetized breech pin 195 and holding it in its firing position. As in the construction of Fig. 1, the breech pin is biased by a spring 197 in such a manner that when free, the breech pin will occupy a loading position, and the movement of the breech pin is limited by a set screw 199 threaded through the upper surface of the gun barrel.

The forward sliding or cocking movement of the hammer 163 is accomplished in this embodi-

ment of my invention by means of a thumb bolt 201 which is threaded into the side of the hammer 163, through a slot 203 formed in one of the walls of the casing 165. The thumb bolt is preferably located so that it may be operated by the thumb of the hand which is grasping the stock of the pistol during use. In the cocked position of the hammer, the rear extension thereof will occupy a sufficiently forward position to permit the supported end 189 of the loading finger to drop behind the end of the extension, thus permitting the breech pin to withdraw under action of spring 197 to its loading position.

As in the previously described embodiment, the casing 165 is arched along its upper edge to provide a magazine 205 with a feed opening 207 and an inspection slot 209, such magazine being capable of holding a substantial number of shot or pellets of the order of twenty-five or more. The magazine is closed at one end by a short rib 208 added to the upper edge of the auxiliary chamber tube 146 and at the other end is closed by the breech block 82 itself, which at this point is of sufficient thickness to provide a well 210 leading to the charge opening into the gun barrel 131, such well being of sufficient length to accommodate one or more pellets. The pellets are fed to the well by gravity and in like manner are fed from the well into the barrel. The provision of a well of this character will thereby enable loading of the gun regardless of whether the gun is directed at an angle below or above the horizon.

In the operation of this gun, the magazine and the well may first be loaded with shot, and then the pump is operated with sufficient strokes to develop the desired pressure throughout all the interconnecting air pressure chambers in the gun, or the pumping may be accomplished before filling the magazine. When the desired pressure has been obtained, the hammer is urged to its forward position through thumb pressure upon the bolt to cock the gun, whereupon along with the cocking of the gun, the breech pin will be withdrawn to its loading position permitting a pellet to drop into the gun barrel. By reason of the fact that the breech pin is magnetized, the pellet will be held against the end of the breech pin.

Upon pulling the trigger to discharge the gun, the breech pin will automatically shift the pellet to the firing position and the breech pin will be locked in this position by reason of the fact that the lower end of the loading finger will ride upon the hammer extension as illustrated in Fig. 6. Such operation of the breech pin is timed to terminate before the hammer strikes the tappet and cause momentary opening the discharge valve.

Opening of the discharge valve in response to such hammer blow, will release a portion of the air under compression between the disc plunger and the valve, which air will discharge through the channel behind the pellet with a force sufficient to eject the pellet at high velocity.

An important feature in the operation of this gun resides in the fact that the openings in the various partitions and the leakage between the disc plunger and the wall of the pump piston is so restricted that upon the sudden release of air through the discharge valve, a decided drop in pressure on the valve side of the disc plunger occurs, causing the existing high pressure on the other side of this plunger to drive the disc plunger forward suddenly and produce an instantaneous cut-off in the valve operation. Following such

sharp-cut-off, the leakage provided through the partitions and by the disc plunger will allow for equalization of pressure throughout the air chamber space in the gun, whereupon the valve spring will return the disc plunger back to its original position, which is shown in Fig. 6.

Inasmuch as the volume of air on the valve side of the disc plunger represents but a small portion of the entire volume of air stored in the various chambers of the pistol, and inasmuch as the valve will close before all the air on the valve side of the spring plunger can discharge, it will be apparent that only an exceedingly small percentage of the air is employed to fire each pellet. Consequently, after each firing and after the pressure has again become equalized, the pressure behind the discharge valve will not have been appreciably diminished from what it was before the previous shot. Such slight drop in pressure per shot is partially compensated for by the fact that the hammer blow which remains the same for each discharge of the gun, will have an increasingly greater effect on the valve discharge, thus tending to uphold the velocity of the pellets discharged from the gun. Consequently, it follows that this repeater type of gun is capable of firing a large number of shots on a single charge of air at velocities above a desired practical minimum, the number depending in part upon the pressure to which the air in the gun is pumped. A moderate amount of pumping will develop a charge in the gun capable of imparting high velocity to a full magazine of shot with little variation between the velocity of successive shots. The firing curve representing the variations in velocity can be controlled in the manufacture of the gun so as to have a rising and/or drooping velocity characteristic between values above a desired minimum value, such curve characteristics being a function of hammer weight, stiffness of hammer spring etc.

The degree of leakage through the partitions and past the disc plunger is preferably made such as to bring about an equalization of pressure throughout the entire air space of the gun within the short period of time which one might normally consume between successive firings of the gun.

The above described embodiment of Fig. 6, has been illustrated as incorporating bolt action in the operation thereof, but the same type of gun may be converted to sleeve action along the lines indicated in the embodiment of Fig. 1. Inasmuch however, as this embodiment of Fig. 6 utilizes hammer action in the firing of the gun as distinguishing from the direct connection of Fig. 1, the breech block would be provided with a depending lug adapted to engage the rear end of the hammer so that upon withdrawal of the pump and gun barrel assembly, the hammer will be urged forward to effect engagement with the trigger.

Such withdrawal of the pump and gun barrel assembly will at the same time enable the breech pin to uncover the well opening to the gun barrel, to enable entrance of one of the pellets, to be subsequently urged to its firing position, upon restoration of the pump and gun barrel assembly to its normal position.

It will be apparent from the above description of my invention, that I have provided a gun powered by air which embodies many new features, cooperating to produce improved results. These features may be applied to rifles as well as pistols. It will be further apparent that the embodiments

described by me fulfill all the objects of my invention, and that while the various features are subject to modifications without departing from the principles embodied therein, I do not desire to be limited in my protection to the details described by me, except as may be necessitated by the prior art and the appended claims.

- I claim:
1. In a gun, a pump and valve assembly comprising a pump barrel having an outlet or discharge end for air under compression, an air duct leading from said discharge end to the firing position of a pellet in said gun, a piston in said pump barrel facing said discharge end, a valve seat at the discharge end of said pump barrel, surrounding the entrance to said air duct, said valve seat having a portion thereof tapering inwardly in the direction of said piston and being of elastic material which is materially deformable under the pressure conditions within said pump barrel, a valve on said elastic valve seat and means for actuating said valve from said valve seat.
  2. In a gun, a pump and valve assembly comprising a pump barrel having a common inlet and discharge opening, an air duct leading from said opening to the firing position of a pellet in said gun, a piston in said pump barrel facing said opening and having a piston rod extending beyond the confines of said pump barrel, a valve seat surrounding said common inlet and discharge opening, said valve seat having a portion thereof tapering in the direction of said piston and being of elastic material which is materially deformable under the pressure conditions within said pump barrel, and a valve on said elastic valve seat of narrowing cross section adapted to be actuated therefrom in response to trigger operation of said gun.
  3. An air gun comprising a pump, a gun barrel supported parallel to said pump, an air duct leading from said pump to the firing position of a pellet in said gun barrel, a magazine adjacent said barrel for holding a plurality of pellets, a feed opening from said magazine to said barrel at a position to the rear of said firing position, a breech pin extending into said barrel and capable of limited movement between said loading position and a point to the rear of said feed opening, a sleeve or casing slidably enclosing the rear portion of said pump and barrel and normally holding said breech pin to said firing position, means enabling partial withdrawal of said barrel from said sleeve or casing independently of said breech pin, a distance substantially equal to the distance between said firing position and said feed opening.
  4. An air gun comprising a pump, a gun barrel supported above said pump in line therewith, an air duct leading from said pump to the firing position of a pellet in said barrel, a magazine adjacent said barrel for holding a plurality of pellets, a feed opening from said magazine to the upper surface of said barrel at a position to the rear of said firing position, a breech pin extending into said barrel from the rear end thereof, a sleeve or casing slidably enclosing the rear portion of said pump and barrel and normally holding said breech pin to said firing position, means enabling partial withdrawal of said pump and barrel from said sleeve or casing a distance substantially equal to the distance between said firing position and said feed opening, and means for restraining movement of said breech pin during such partial withdrawal of said pump and

barrel to effect exposure of said feed opening to the interior of said barrel.

5. An air gun comprising a compressed air chamber, a barrel supported above said compressed air chamber in line therewith, an air duct from said compressed air chamber to the firing position of a pellet in said barrel, a feed opening in said barrel for feeding pellets individually into said barrel for placement at the firing position, a sleeve or casing enclosing the rear portion of said compressed air chamber and barrel and arched along the upper edge to form a magazine for the reception of a plurality of pellets, said magazine having one end thereof terminating at said feed opening.

6. An air gun comprising a compressed air chamber, a tubular element including a barrel supported axially therein and above said air chamber in line therewith, an air duct from said air chamber to the firing position of a pellet in said barrel, a feed opening in said barrel for feeding pellets individually into said barrel for placement at the firing position, a sleeve or casing enclosing the rear portion of said air chamber and tubular element and forming with said tubular element a magazine for the reception of a plurality of pellets, said magazine having one end thereof terminating at said feed opening.

7. An air gun comprising a pump having a fixed hollow cylindrical piston terminating in a piston head facing toward the muzzle end of the gun and having a check valve therein, and a pump cylinder in slidable engagement with said fixed hollow cylindrical piston, said pump cylinder having a check valve at the muzzle end thereof enabling entrance of air under pressure into said fixed hollow cylindrical piston to function as a storage chamber for air under pressure.

8. An air gun comprising a pump having a fixed hollow cylindrical piston terminating in a piston head facing toward the muzzle end of the gun and having a check valve therein, a pump cylinder in slidable engagement with said fixed hollow cylindrical piston, said pump cylinder having a check valve at the muzzle end thereof enabling entrance of air under pressure into said hollow cylindrical piston to function as a storage chamber for air under pressure, a barrel supported above said pump and in line therewith, an air duct extending from said hollow piston storage chamber to the firing position of a pellet in said barrel, and manually controlled valve means for releasing a predetermined portion of the compressed air in said storage chamber into said air duct to discharge said pellet.

9. An air gun comprising a gun barrel, a compressed air storage chamber, an air duct leading from said storage chamber to the firing position of a pellet in said barrel, a normally closed valve between said storage chamber and said firing position, manual operated means for momentarily controlling the opening of said valve to release a charge of air from said storage chamber, and piston means partitioning said compressed air storage chamber and movable in the direction of said valve in response to a differential air pressure created by said charge release.

10. An air gun comprising a gun barrel, a compressed air storage chamber, an air duct leading from said storage chamber to the firing position of a pellet in said barrel, a normally closed valve between said storage chamber and said firing position, manual operated means for momentarily controlling the opening of said valve to release a charge of air from said storage chamber,

10 a leakage plunger partitioning said storage chamber and movable in the direction of said valve in response to a differential air pressure created behind said plunger by said charge release, and a plunger restoring spring between said plunger and said valve for restoring said plunger to its normal position as such differential air pressure subsequently approaches the zero value.

15 11. A gun comprising a gun barrel, an air storage chamber, said gun barrel and storage chamber terminating in a breech block, an air discharge channel through said breech block and connecting said air storage chamber to the firing position of a shot in said gun barrel, valve means normally blocking said discharge channel and extending to the rear of said breech block, a breech pin movable in said barrel from a loading position to said firing position and also extending to the rear of said breech block, trigger operable means for urging said breech pin to said firing position and locking the same and subsequently actuating said valve means to effect a discharge of air against said shot.

20 12. In an air gun, an air storage chamber, a gun barrel, valve means for controlling discharge of air to said gun barrel, a hammer in said gun movable from a cocked position along a path below and substantially in line with said storage chamber to a discharge position to effect operation of said valve, a casing for said gun having a slot in a side wall thereof exposing a portion of said hammer, and a bolt extending into said casing through said slot and connecting with said hammer to enable manual shifting of said hammer to its cocked position.

25 13. An air gun comprising a gun barrel, a compressed air storage chamber, an air duct leading from said storage chamber to said gun barrel, a valve normally closing said duct to the flow of air between said storage chamber and said gun barrel, and piston means normally disposed at an intermediate point in said storage chamber, an air pressure equalization passage interconnecting the portions of said storage chamber on each side of said piston means, said piston means being movable in the direction of said duct in response to a differential air pressure created by the opening of said valve.

30 14. An air gun comprising a compressed air chamber, an air duct leading therefrom, valve means normally closing said air duct to the discharge of air from said air chamber, said valve means comprising a valve component and a valve seat component, one of said components being of rubber like material and stretchable against the air pressure in said air chamber, and means for stretching said component to the point where said component snaps away from the other to effect a sudden full opening of said valve means and permit a discharge through said air duct from said air chamber.

35 15. A gun comprising a gun barrel, an air storage chamber, said gun barrel and storage chamber terminating in a breech block, an air discharge channel through said breech block and connecting said air storage chamber to the firing position of a shot in said gun barrel, valve means normally blocking said discharge channel and extending to the rear of said breech block, a breech pin movable in said barrel from a loading position to said firing position and also extending to the rear of said breech block, trigger operable means for urging said breech pin to said firing position and subsequently actuating said

valve means to effect a discharge of air against said shot.

16. An air gun comprising a gun barrel, a compressed air storage chamber, an air duct leading directly from said storage chamber to said gun barrel, a single valve normally closing said duct, trigger-released means for directly and instantaneously opening said valve, and means controlled by the discharge through said duct of a metered quantity of air for automatically closing 10 said valve.

17. An air gun comprising a gun barrel, a compressed air storage chamber, an air duct leading directly from said storage chamber to said gun barrel, a single valve normally closing said duct, trigger-released means for directly and instantaneously opening said valve, and air-actuated piston means controlled by the discharge through said duct of a metered quantity of air for automatically closing said valve.

WILLIAM S. WELLS.
